Patented Sept. 29, 1925.

UNITED STATES PATENT OFFICE.

MERTON L. DODGE, OF SEATTLE, WASHINGTON, ASSIGNOR TO SEATTLE ASTORIA IRON WORKS.

STOPPING DEVICE.

Application filed April 24, 1923. Serial No. 634,316.

To all whom it may concern:

Be it known that I, MERTON L. DODGE, a citizen of the United States, and a resident of Seattle, King County, Washington, have invented certain new and useful Improvements in Stopping Devices, of which the following is a specification.

This invention relates to an automatic stopping device and has for its object to provide such a device to be used as a means for automatically stopping a can sealing machine.

More particularly the invention resides in the provision of a stopping device for use with can sealing machines of that class which operate under the control of automatic stop mechanism like, or of a similar character to that as disclosed in my co-pending application for "Automatic stop for can making machines", filed February 6, 1923, under Serial No. 617,397.

Explanatory of the invention I will state here that can sealing machines of the type with which the present device is used are, as a rule, equipped with means for applying identifying numbers to the ends of the cans as they pass through the machine and these numbers are manually changed whenever the character of the canned product is changed. For example, cans containing red salmon would be given a different serial number from those containing another product. In most factories an attendant is stationed at each machine to watch the cans as they are delivered to the sealing mechanism, and when the attendant notes a change in the character of the product, or, when he is notified by the can filler that a change has been made, he will stop the machine at the proper time and change the numbers of the stamping or printing die.

Such machines also are equipped with mechanism whereby they will be automatically stopped should a can body be delivered into the machine without the delivery of a cover or end therefor, and it is with machines so equipped that the present device is intended to be used.

The object of this invention, therefore, has been to provide a substitute for a can that may be placed by a person, who may be the can filler, on the conveyor whereby the filled cans are delivered to the sealing machine and which will act automatically to stop the machine at the proper time so that the change

of numbers can be made, or it can be used for the purpose of stopping the machine at the end of a run and thereby make it unnecessary for an attendant to be stationed at the machine for these particular purposes.

In accomplishing the objects of the invention I have provided the improved details of construction the preferred forms of which are illustrated in the accompanying drawings, wherein—

Figure 1 is a side elevation of a part of a machine that is adapted to seal the ends of cans, and which embodies means whereby it may be stopped by a device of the present type of construction.

Figure 2 is a side view, partly in section, of the stopping device.

Figure 3 is an enlarged, horizontal section taken on the line 3—3 in Figure 1.

Figure 4 is a side view of a stopping device of an alternative type.

Referring more in detail to the drawings—

1 designates, as a whole, a machine with which the present type of stopping device is adapted to be used, and 2 designates a can body that is being moved into the machine by means of a conveyer belt 3 operating about a driven sprocket wheel 30. Supported by the frame of the machine are vertical guide standards 4 wherein a stack of can ends 5 are located and which are adapted to be delivered, one at a time, from the lower end of the stack into the machine and to be advanced accordingly as the can bodies 2 are advanced. The can end feeding mechanism, not shown, is operated under the control of a trip lever 6 that is extended into the path of the advanced cans, and which is engaged by each passing can body and is actuated thereby to effect the operation of the feeding mechanism whereby the ends are delivered singly into the machine. During the operation of the machine the ends are picked up by a suction cup arrangement and are placed thereby upon the ends of the bodies and are secured to the bodies by means of a double seamer device, not illustrated.

In such machines provision has been made whereby, should the mechanism that feeds the ends of the cans into the machine for any reason fail to operate and thereby not deliver a can end, or should the body supply become exhausted, the machine will be auto-

- 2
- matically stopped; this being accomplished in the machine herein illustrated by the operation of mechanism under the control of levers 10 and 11 that are respectively supported in the paths of travel of the ends and bodies. These levers are so mounted that ordinarily they will be simultaneously engaged by the body and end of a can, and when both are engaged and actuated, the machine will continue to operate but should one lever be moved without the other, the machine will be stopped. This would be the result if a can body would enter the machine without an end being delivered.
15. The stopping device, which I have provided and which may be advanced by the conveyor into the machine to stop the same, comprises a cylindrical body portion 15 of the same diameter as the cans which are being delivered to the machine, and provided at its opposite ends with reduced neck portions 16 upon which end plates 17 are fixed by means of screws 18. The diameter of the plates 17 is the same as the body portion 15 and they are located concentric therewith. The length of the can between the outer faces of the plates would be slightly less than the length of the can bodies 2 to prevent damage to the machine should these devices pass through the machine. The construction provides annular recesses 19 between the plates 17 and the body 15.
- When it is desired to stop the machine one of the stopping devices is placed on the conveyor 3 in the same position as a filled can would ordinarily be placed and it is carried by the conveyor into the machine. When it passes the end of the lever 6, instead of actuating it pivotally as the ordinary can 2 would, it passes by without effecting a movement and no cover is delivered to the machine. This is due to the fact that the recessed end of the device lies in the same plane as the lever 6 and permits the can to pass without effecting any movement of the lever. Then, when the device passes into the machine and engages the lever 11 and actuates it and the lever 10 is not simultaneously actuated, due to the absence of a can end, the machine will be stopped, due to the operation of parts as is described in the application previously referred to.
- It will be noted that the normal position of the lever 6 provides that it will engage the cans 2 near their lower ends as they are advanced and for this reason I have located the channels 19 adjacent the ends of the body of the stopping device; the channels being provided at each end so that it will make no difference whether the device is inverted or not. If the location of the lever 6 should be raised or lowered, this of course, would

necessitate a relocation of the channels or recesses 19.

While I have provided that the machine here illustrated be stopped as a result of the lever 6 not being actuated, it is readily apparent that machines that are equipped with automatic stop mechanism of the type illustrated and described in my co-pending application can be stopped by the passing of a device through without effecting the actuating of the lever 11. In such instance the recess 19 would be located in accordance with the location of the lever 11 and in the present instance would be centrally of the body as is shown in Figure 4.

The device may be made of a heavy material so that it will be of substantially the same weight as a filled can, so that it would effectively serve its purpose.

Having thus described my invention, what I claim as new therein and desire to secure by Letters-Patent, is:

1. In a machine of the class described, the combination with mechanism for feeding articles into the machine and a trip lever adapted to be moved by each article as it is delivered and which, if not actuated, operates to stop the machine, of an automatic stopping device, comprising a body conforming in general outline to the shape of the said articles and provided with a recess which will permit the device, when used in lieu of one of said articles, to pass by the lever without causing its movement.

2. In a machine of the class described, the combination with mechanism for feeding articles into the machine and a trip lever adapted to be moved by each article as it is delivered and which, if not actuated, operates to stop the machine, of an automatic stopping device, comprising a body conforming in general outline to the shape of the said articles and provided with an encircling recess which will permit the device, when used in lieu of one of said articles, to pass by the lever without causing its movement.

3. The combination set forth in claim 1, in which the automatic stopping device, comprises a cylindrical body portion with reduced opposite ends forming annular recesses thereabout.

4. The combination set forth in claim 1, in which the automatic stopping device, comprises a cylindrical body with reduced end portions and supporting plates of the same diameter as the body fixed co-axially to the ends thereof and forming annular channels about the ends of the body.

Signed at Seattle, King County, Washington this 18th day of April 1923.

MERTON L. DODGE.
